CARL O. BRUNO, OF LOS ANGELES, CALIFORNIA, ASSIGNOR, BY DIRECT AND MESNE ASSIGNMENTS, TO BIGELOW-BRUNO MANUFACTURING COMPANY, OF CHICAGO, ILLINOIS, A CORPORATION OF ILLINOIS.

TIMER FOR INTERNAL-COMBUSTION ENGINES.

Application filed July 2, 1920. Serial No. 393,547.

To all whom it may concern:

Be it known that I, CARL O. BRUNO, a citizen of the United States, residing at Los Angeles, in the county of Los Angeles and State of California, have invented new and useful Improvements in Timers for Internal-Combustion Engines, of which the following is a specification.

This invention relates to timers for internal combustion engines of the type mounted upon the end of a cam shaft and arranged adjacent the fan belt and fan of the engine.

In timers of this character as now generally constructed a terminal is provided for 15 separate wires leading to the spark plugs of the respective cylinders of the engine, said terminals being equally spaced around the periphery of the timer. By this arrangement in a timer employed in connection with 20 a four cylinder engine two of said terminals are at the side of the timer adjacent the fan belt of the engine and in a position where they are not readily accessible. The wires leading to these two terminals are subjected 25 to dirt, water and oil thrown by the fan belt so that much difficulty has been experienced through the rotting and wearing of the insulation of these two wires.

One of the wires leading to these two 30 terminals is also in such a position that if the fan belt becomes loose or the wires sag, it will cut through said wires, and the other wire leading to these two terminals is in a 35 position adjacent the connecting rod for actuating the timer so that said wire is liable to rest against said rod resulting in a short circuit should the insulation of said wire be worn away. As a result of the 40 above described conditions much difficulty has been experienced through the short circuiting of the wires leading to these two terminals as well as through the necessity of continually repairing or replacing these wires as they become worn. The wires leading 45 to the other two terminals of the timer are at the side thereof away from the engine and in a position where they are not subjected to the various wearing actions above set forth. These wires are also so 50 positioned upon the timer as to be readily accessible for assembling, inspecting and repairing the parts.

It is the object of the present invention to provide a timer construction necessitat-

ing the employment of but two terminals 55 and wires leading therefrom for a four cylinder engine, these two terminals and wires being arranged at the outer side of the timer where they are readily accessible and not subjected to the above enumerated destructive actions.

It is a further object of the invention to provide a timer construction arranged to provide a spark in two of the cylinders at the same time, the spark in one of said cylinders being a working spark adapted to ignite a combustible charge within said cylinder, while the spark in the other cylinder is an idle spark made at the beginning of the suction stroke within said cylinder so as to cause no explosion therein, but adapted to burn off any accumulation upon the points of the spark plug and thereby prevent fouling of the same.

The invention will be readily understood 75 from the following description of the accompanying drawings, in which—

Figure 1 is a somewhat diagrammatic illustration showing a transverse section through the improved timer and the wiring 80 connections between the same and the spark plugs of the respective engine cylinders which are shown in longitudinal section.

Fig. 2 is a longitudinal section on the line 2—2 of Fig. 1.

Fig. 3 is a longitudinal section through the cylinders of the engine showing a somewhat modified wiring connection to the spark plugs from the improved timer.

The timer is mounted upon the end of the 90 usual cam shaft 1, said cam shaft being disposed in a horizontal plane with the end thereof projecting beyond the engine casing 2 at one side of said casing. The timer comprises a usual casing 3 received over the end 95 of shaft 1 and abutting against the engine casing 2 with the casing held in position by any suitable means such as the usual retaining clip not shown. A usual lug 4 extends from the top of the casing and is connected with a usual actuating rod 5 for rotating the casing relative to the shaft 1. The usual ring of insulating material as shown at 6 is received against the inner surface of casing 3, and within said ring are embedded two of the usual four contact strips 7 connected to terminal bolts 8 projecting through the casing in usual manner. These two contact

strips are at the side of the timer away from the engine and are arranged in the usual position occupied by the two contact strips at this side of the timer. It will thus be understood that said contact strips are spaced apart a distance equal to one-fourth of the periphery of the timer casing.

The opposite side of the timer presents an unbroken surface of the insulator ring 6, this side of the insulator ring being, preferably, retained in position within the timer casing by means of a set screw 9, while the opposite side of the insulator ring is positioned by means of terminal bolts 8 in usual manner. The terminal bolts are provided with the usual lock nuts 10 and retaining nuts 11 adapted to clamp the ends of connecting wires between the nuts 10 and 11.

The contact maker of the timer consists of diametrically opposed contacts rotatable with shaft 1 so that a contact is alternately made with strips 7 at every quarter revolution of the cam shaft. As an instance of this arrangement the contact maker is shown as a collar 13 fixed upon the end of shaft 1 in usual manner and retained in position by nut 14. Sleeves 15 project diametrically from collar 13, said sleeves being open at their outer ends and each receiving a contact pin 16 arranged for wiping contact against ring 6 and contact strips 7. The pins may be urged outwardly by means of usual springs 17.

In the form of the invention shown in Fig. 1, the four engine cylinders are shown at A, B, C and D; and are each provided with a usual grounded spark plug 20. The spark plugs are connected by wires 21 to the usual coils A', B', C' and D'.

As will be readily understood, the cylinders, pistons and valves of the engine are arranged in usual manner, so that the pistons of cylinders A and D and the pistons of cylinders B and C, are similarly arranged relative to the crank shaft; and the valve mechanism is such that, for example, as cylinder A is on its firing stroke, cylinder D is sucking in a new charge, cylinder B is compressing, and cylinder C is exhausting.

The coils for cylinders A and D are connected in multiple parallel by a wire 23 to one of the terminal bolts 8 and coils B' and C' are similarly connected to the other terminal bolt.

Thus it will be seen that at alternate quarter revolutions of the engine, a contact will be closed through coils A' and D' to cause a spark in cylinders A and D. The spark in the cylinder containing a compressed charge, say cylinder A, will cause an explosion and a working stroke, while the spark in cylinder D, in which there is no charge will be an idle spark. The next time a spark occurs in these cylinders, which will be two strokes later in the cycle of operation, the spark in cylinder

D will be the working spark while the spark in cylinder A is an idle spark.

In similar manner cylinders B and C will be alternately fired between firing of cylinders A and D, through the contacts made by the second contact strip 7.

In the modification illustrated in Fig. 3, wires 23 are each connected to a single coil A² and B². The spark plugs of each pair of cylinders A—D and B—C, consist of a grounded plug 20 and an insulated plug 20', said pairs of plugs for cylinders A—D and B—C being connected in series by a wire 21 to the coils A² and B² respectively. By this arrangement it will be seen that each time a circuit is made through the wires leading to coils A² and B² respectively, in the manner previously described, a spark will occur in cylinders A and D and B and C as above set forth.

It will thus be seen that I have provided a timer construction by the use of which the regular sequence of operation is maintained in the engine cylinders, a spark occurring in each cylinder upon alternate strokes, with alternate ones of said sparks a working spark and an idle spark. Furthermore it will be observed that the double end construction of the contact maker permits of the elimination of the two timer terminals at the side thereof which is inaccessible, and which are liable to become inoperative from various causes.

Various changes may be made without departing from the spirit of the invention as claimed.

What is claimed is:

1. A timer for four cycle internal combustion engines, comprising a rotatable contact maker having diametrically opposed contacts, a casing disposed over said contact maker and stationary contacts disposed circumferentially in said casing, said stationary contacts being less in number than the number of the cylinders of the engine to which said timer is applied.

2. A timer for internal combustion engines having a plurality of cylinders, comprising a rotatable contact maker having diametrically opposed contacts, a casing disposed about said contact maker, stationary contacts arranged circumferentially in said casing and engageable with the contacts of said contact maker, said stationary contacts being less in number than the number of cylinders of the engine to which said timer is applied.

3. A timer for internal combustion engines having a plurality of cylinders, comprising a rotatable contact maker having diametrically opposed contacts, a casing disposed about said contact maker, stationary contacts arranged circumferentially in said casing and engageable with the contacts of said contact maker, said stationary contacts

being less in number than the number of cylinders of the engine to which said timer is applied, all of said stationary contacts being arranged upon one side of a diameter of said casing.

4. A timer for internal combustion engines having a plurality of cylinders, comprising a rotatable contact maker having a plurality of radial arms, yieldable contacts carried by said radial arms and a casing disposed over said contact maker, and having a plurality of stationary contacts arranged circumferentially therein, said contacts being less in number than the number of cylinders of the engine to which said timer is applied.

5. A timer for internal combustion engines having a plurality of cylinders, comprising a contact maker having a pair of oppositely disposed arms, a casing disposed about said contact maker, a plurality of stationary contacts circumferentially arranged within said casing and adapted to be engaged by said arms, said stationary contact being disposed upon one side of a diameter of said casing and being in number equal to one-half of the number of the cylinders of the engine to which the timer is applied.

In testimony whereof I have signed my name to this specification.

CARL O. BRUNO.
